ABSTRACT OF THE DISCLOSURE

Resilient mounting means for securing the opposite ends of dividers in a tray or similar structure having opposing walls between which the divider extends, the mounting means comprising an extruded strip-like member formed from a resilient material such as rubber or flexible plastic, the member being of generally elongated rectangular configuration having a divider receiving slot extending lengthwise along one of its sides and a plurality of spaced apart gripping elements extending lengthwise along its opposite side, the insertion of a divider into the slot serving to flex or arch the gripping elements into clamping engagement with the wall surface engaged by the mounting member.

BACKGROUND OF THE INVENTION

Modern merchandising has placed ever increasing emphasis on the display of the merchandise being sold and its ready accessibility to the customer for inspection and purchase. To this end, the practice of binning merchandise has become more and more prevalent. Binning refers to the practice of placing the merchandise in bins which are of a size to just nicely receive the articles when stacked one upon the other or otherwise arranged in the bin. Binning, of course, requires that the display counters, which are usually walled, be provided with dividers which divide the available space into as many bins as are desired to contain the articles being displayed. In order to be flexible and accommodate different numbers and sizes of articles at different times, the dividers must be readily movable from one position to another, and over the years numerous divider clips, usually formed from metal, have been proposed. These clips are designed to be secured to the walls of the display table with flanges arranged to engage the end edges of the dividers. Diverse designs of clips are available to suit different conditions of use, such as forming corners, T-joints, crosses, and the like.

Clips of the character described have a number of disadvantages. They are relatively expensive and different style clips must be kept on hand for different applications, depending upon where the dividers are to be located and their relationship to each other. In addition, where the dividers are made of glass they tend to be scratched and chipped by the metal clips, particularly if the clamping portions of the clips have been bent so as to be too tight for the thickness of glass being inserted in them. Alternatively, if the clips are bent in the opposite direction and become too loose, they will no longer securely hold the dividers in place. While the dividers themselves are generally of standard thicknesses, many of the walled display trays with which they are used vary in depth and also in thickness, with the result that it is often impossible to find a fitting precisely suited to the particular need. Similarly, if the dividers are of substantial depth, clips must be provided at both tops and bottoms, and possibly at intermediate points, which poses additional problems. Various forms of essentially rigid plastic clips have also been proposed, but in general they suffer from many of the same disadvantages found in metallic clips.

2**SUMMARY OF THE INVENTION**

In contrast to the foregoing, the instant invention provides resilient mounting strips for dividers which may be formed as a continuous extrusion, wound into rolls, and supplied to the user in a form such that the desired length for any given application may be readily severed from the supply roll.

Mounting strips in accordance with the invention may be formed from rubber, either natural or synthetic, or from any of the numerous plastic materials which have elastic qualities, such as the so-called elastic vinyls.

The configuration of the mounting strips is important if they are to successfully hold the dividers in place. Essentially, the strips are of generally rectangular configuration having relatively wide front and rear sides with narrower ends. A divider receiving groove is formed lengthwise along the center of the front side. The groove is, however, narrower at its mouth than at its base, and the mouth is narrower than the thickness of the divider which is to be inserted in the groove.

The rear side of the member is provided with opposing sets of inwardly inclined gripping elements which are in the nature of flexible fins extending lengthwise of the member, the opposing sets of fins lying to each side of a relatively narrow flexible bridge underlying the longitudinal groove, the bridge connecting together the opposite halves of the member.

When the end edge of a divider is inserted in the mouth of the groove and seated against its base, the mouth of the groove is expanded and the opposite halves of the member are flexed laterally, the member bending or flexing about its bridge. The bridge is in effect arched so that the opposing sets of fins are forced into biting engagement with the wall surface which they contact. Since the opposing sets of fins are inwardly directed, they effectively wedge against the wall surface and resist lateral shifting or rolling movement.

Being formed from a flexible elastic material, the mounting strips do not scratch either the divider or the wall surfaces engaged thereby. It will be understood, of course, that the length of the divider will be such that its opposite ends will lie in close proximity to the opposing wall surfaces or other dividers between which the divider in question is to extend, the divider thus serving to effectively force the mounting members into engagement with the opposing supporting surfaces.

THE DRAWINGS

FIGURE 1 is a perspective view of a walled display table in which several dividers have been mounted utilizing the resilient mounting means of the instant invention.

FIGURE 2 is a perspective view of one of the mounting members seen in FIGURE 1.

FIGURE 3 is an end elevational view of the mounting member in its original condition before the insertion of a divider.

FIGURE 4 is a vertical sectional view illustrating the manner in which the divider acts to flex or arch the mounting member and press the fins into clamping engagement with the supporting wall surface.

DESCRIPTION OF THE PREFERRED EMBODIMENT

Referring first to FIGURE 1, there is illustrated a modern walled display table 1 having a top 2 enclosed by front wall 3, rear wall 4, and opposing end walls 5 and 6. In the embodiment illustrated the display table is provided with a storage compartment underlying the top 2 accessible through sliding doors 7 and 8.

The walled top of the display table is divided into compartments or bins 9, 10 and 11 by means of the

dividers 12 and 13 extending between the front and rear walls 3 and 4, respectively. In accordance with the invention, the dividers are fixed in place by mounting members 14 which are urged into clamping engagement with the front and rear walls by means of the dividers.

As seen in FIGURES 2 and 3, each of the mounting members 14 is of generally rectangular configuration, having a relatively wide front wall 15 with its opposite side edges rounded at 16 to join the opposite end walls 17 and 18. A longitudinal channel or groove 19 extends centrally throughout the length of the member, the groove having a mouth 20 which is narrower than its base 21, the mouth and base being joined by inclined side walls 22 and 23.

The longitudinal groove divides the member into opposing halves 24 and 25, there being an inset portion 26 underlying the base 21 of groove 19 defining a relatively narrow bridge 27 interconnecting the opposite halves of the member.

Opposing sets of fins or gripping elements 28, 29 project outwardly and inwardly from the rear wall of the body halves 24 and 25, respectively, the fins in each set lying in spaced apart relation in the manner illustrated. The number of fins employed does not constitute a limitation on the invention, although preferably there will be a plurality of such fins in each set.

FIGURE 4 illustrates the mounting member 14 in its position of use, in this instance the mounting member receiving one end of the divider 12 and securely mounting it relative to the front wall 3 of the display table shown in FIGURE 1. It will be noted that the divider 12, when inserted in the groove 19 acts to flex the mounting member laterally, the opposite halves 24 and 25 of the member flexing about the bridge 27. The sets of fins 28 and 29 are compressed against the supporting wall 3 and enter into clamping engagement with the wall. Lateral displacement of the member in the direction of the arrow A is resisted by the fins 28, whereas lateral movement in the direction of arrow B is resisted by the fins 29. The compressed fins also act to urge the mounting member outwardly, i.e., in the direction of the divider 12, and hence a wedging or locking action is obtained. The side walls 22 and 23 of the groove 19 engage the opposite sides of the divider and hold it against movement lengthwise of the groove and at the same time prevent any looseness or rattling of the divider. Being formed from an elastic material, the mounting member effectively cushions the divider and will not scratch or mar its edges. Yet when it is desired to remove the divider it may be manually displaced lengthwise of the groove for removal,

Size does not constitute a limitation on the invention, nor does the particular configuration of the sets of fins which may be rectangular in cross-section, tapered or terminate in pointed edges. If the member is molded, the fins may be interrupted or in the nature of a multiplicity of individual fingers, although a preference is expressed for extruding the member in continuous lengths, in which event the fins will be continuous throughout the length of the extrusion. By providing the strips in continuous lengths, the user may sever such continuous lengths transversely into the desired size for a given installation. Even on reuse, should a subsequent installation require mounting members of lesser lengths than those which are available, the available members may be cut to the required lengths for the new installation.

The embodiments of the invention in which an exclusive property or privilege is claimed are defined as follows:

1. A mounting member for display table dividers and

the like comprising a length of distortable resilient material having front and rear surfaces, a groove extending centrally throughout the full length of the front surface of said member for receiving an end edge of a divider, said groove having a mouth and a base and being narrower at its mouth than at its base, said groove acting to effectively divide said member longitudinally into opposing halves connected together by a bridge member defined between the base of said groove and the rear surface of said member, a plurality of longitudinally extending fins projecting outwardly from the rear surfaces of the opposing halves of said mounting member, said fins being arranged in opposing sets lying on opposite sides of said groove and inclined inwardly toward each other, the opposing halves of said member and the fins carried thereby being displaceable relative to each other about said bridge member upon the insertion in said groove of a divider of a width to expand the mouth of said groove outwardly.

2. The mounting member claimed in claim 1 wherein the central portion of said rear surface is relieved to decrease the thickness of said bridge member.

3. The mounting member claimed in claim 2 wherein said member is of generally rectangular configuration, the front and rear surfaces lying in generally parallel relation and joined together at their outermost edges by generally parallel end wall surfaces.

4. In combination with a display table or the like having opposing wall surfaces and a removable divider extending between said opposing wall surfaces, mounting members detachably connecting the opposite ends of said divider to said opposing wall surfaces, said mounting members each comprising a length of distortable resilient material having front and rear surfaces, a groove extending centrally throughout the length of the front surface of said member, said groove having a mouth and a base and acting to divide the mounting member into opposing halves connected together by a bridge member lying between the base of said groove and the rear surface of said mounting member, and a plurality of longitudinally extending fins projecting outwardly from the rear surfaces of the opposing halves of said mounting member, said fins being arranged in opposing sets lying on opposite sides of said groove and inclined inwardly toward each other, the mouth of said groove being narrower than the thickness of said divider, whereby when said divider is inserted in said groove, the opposite halves of the mounting member will be flexed about said bridge in the direction of the wall surface contacted by the rear surface of said mounting member, thereby wedging said fins into clamping engagement with the said wall surface.
